(57) **CLAIM**

The ornamental design for a barbell collar, as shown and described.

DESCRIPTION

FIG. 1 is a front perspective view showing a new barbell collar;

FIG. 2 is a rear perspective view of the barbell collar of FIG. 1;

FIG. 3 is a front view of the barbell collar of FIG. 1;

FIG. 4 is a rear view of the barbell collar of FIG. 1;

FIG. 5 is a left-side view of the barbell collar of FIG. 1;

FIG. 6 is a right-side view of the barbell collar of FIG. 1;

FIG. 7 is a top view of the barbell collar of FIG. 1; and,

FIG. 8 is a bottom view of the barbell collar of FIG. 1.

The broken lines showing portions of the design are included for the purpose of illustrating portions of the design that form no part of the claimed design.

1 Claim, 8 Drawing Sheets
